UNITED STATES PATENT OFFICE.

SAMUEL GOLDSTEIN, OF NEW YORK, N. Y.

PRESSING MACHINE.

Application filed December 10, 1926. Serial No. 153,939.

My invention relates to a pressing machine and more particularly is intended for embodiment in a machine for use in clothing factories for pressing the edges, seams and other thickened portions of a garment required to be pressed and smoothed down.

The general object of my invention is to provide a machine of the indicated type characterized by the facility and speed with which the pressing may be done, to economize in the matter of time as well as to provide a machine for effectively performing the pressing operation on the garment.

The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is a side elevation of the machine.

Figure 2 is a longitudinal vertical section of the pressing machine embodying my invention.

Figure 3 is a plan view thereof.

Figure 4 is a vertical section through one of the bucks or pressing assemblages.

Figure 5 is a section on the line 5—5 of Figure 4.

Figure 6 is an enlarged sectional plan view of the means for rocking the carrier of the movable buck or pressing assemblage.

Figure 7 is an inverted plan view of the back plate.

In carrying out my invention in accordance with the illustrated example, which is intended for use in garment factories, a table 110 is provided on the frame 10 of the machine, on which table is mounted a fixed pressing assemblage or buck 11. A vertical, movable pressing assemblage or buck 12 is adapted to co-act with the buck 11 by being brought downward on to the same or raised above the same for the entrance of the garment. The movable buck 12 is held to carrying means which in the preferred form consists of a bell crank 13 rockable on a horizontal pivot 14. The machine is equipped with a plurality of the pressing assemblages and their appurtenances, is turnably mounted, and use is made in the form shown of a de-

pending sleeve 15 on frame 10, turning about a fixed vertical standard 16 rising from a suitable base 17 and having a collar 18 on which sleeve 15 rests.

Each bell crank 13 has pivotally connected therewith a link 20, the lower end of which is pivoted to a treadle 21, said treadle being pivoted between its ends as at 22 on depending bracket members 23 on frame 10. The lower arm 24 of each bell crank 13 has a roller 25 thereon which is adapted to frictionally engage a roller 26 on treadle 21. Roller 26 (see Figure 6) is mounted on a U-shape slide 27 movable on treadle 21 by reason of transverse pins 28 carried by said slide 27 and adapted to move in slots 29 in treadle 21. A coil spring 30 abuts at one end slide 27 and the other end transverse member 31 of treadle 21, there being a pin 32 axially disposed in said spring, one end being held to slide 27 and the opposite end passing through transverse member 31. At member 31 the pin 32 is threaded and has a nut 33 thereon held against longitudinal movement by member 31 and adapted to move the pin 32 and slide 27 to adjust the tension of spring 30. Thus the slide 27 with the roller 26 may yield along the treadle 21.

By depressing treadle 21 its link 20 will rock the bell crank 13 in a way to lower buck 12 against buck 11. When the pressure of the treadle 21 is relieved and the outer arm of said treadle 21 rises, the inner arm of said treadle will exert a downward pull on arm 24 and bell crank 13 and will cause said arm 24 to move downwardly thereby causing roller 25 to engage roller 26 and exert rolling pressure on said roller 26 which latter roller will yield sufficiently to pass roller 25 and thereby hold the bell crank 13 raised, thus maintaining buck 12 raised. Treadle 21 has a foot piece 34 pivoted thereto as at 35. Said foot piece has a depending pin 36 adapted to engage the floor where the machine is emplaced. With the pin 36 in contact with the floor, a depression of foot piece 34 will cause the treadle 21 to be rocked vertically on its pivot 22, so that the end having roller 26 will be depressed to disengage the roller 25. A retractile spring 37 exerts an upward pull on treadle 21 at one end, causing the other end connecting with the link 20 to be low-

ered, and, through said link 20, causing bell crank 13 to be rocked. This causes buck 12 to be moved to the raised position away from fixed pressing buck 11.

5 The numeral 38 indicates a balance weight on each treadle 21 near link 20.

Each pressing assemblage 11 and 12 is the same and it will therefore suffice to describe it as illustrated in detail in Figures 10 2, 4 and 5. The numeral 40 indicates a facing cloth on the pressing assemblage directly back of which is wire mesh 39 and back of the wire mesh is a perforated plate 41 against the back of which lies an asbestos sheet 42. The facing assemblage is completed by a back plate 43. Behind the back plate 43 is a burner and means to supply water to chambers in the back plate 43. Thus a sinuous heating tube 44 is provided directly adjacent the back plate 43, which is continuous with a pipe 45 leading to water channels 46 in back plate 43, said channels 46 being all connected by a transverse passage 146.

25 The numeral 47 indicates the inlet end of the sinuous pipe 44, said inlet 47 having a valve 48 of any approved form, here shown as having a lever 49 connected to the valve stem to lift the valve, permitting the water to flow. A burner 50 is disposed adjacent sinuous pipe 44 for heating the same and back plate 43, for generating steam to moisten the garment for the pressing operation. Said burner is supplied by gas pipe 35 51 connecting with the burner 50 of buck 12.

A branch hose 52 leads from gas pipe 51 to the burner of the other buck. The gas pipe 51 connects by its inlet end 53 with a header 54 encircling standard 16 near 40 base 17, so that it receives gas from the main supply pipe 55 through a port 56 and an annular passage 57. The numeral 58 indicates a water pipe leading to one valve 48 of head 12 and a branch hose 59 leads to 45 the other valve 48 of a buck 11. Water pipe 58 has its inlet terminal 60 communicating with an annular water chamber 61 in header 54, which chamber 61 is supplied by a water supply pipe 62.

50 With the above described machine the operator turns the table 110 and therefore turns frame 10 and the several bell cranks 13, and turns also the pairs of presser bucks 11, 12. Turning with the table and frame 55 are the described assemblages of gas and water pipes, the supply header 54 thereof and the several treadles 21. The garment having been pressed by the user of the machine, the table and frame are given a turn 60 to bring the next succeeding bell crank 13 and two bucks 11, 12 to a position adjacent the operator.

A drying period is required before stacking the garments and this is provided for 65 by the turning of the table through a com-

plete revolution so that as a pressed garment approaches the operator it is removed from a buck 11 arriving at the operator and a new garment emplaced on the buck.

Suitable latch means is provided to hold 70 the turnable parts against movement. I have shown a vertically rockable lever 65 pivoted on the pin 22 of each treadle 21 and adapted at its lower end 66 to enter a notch 67 in the floor. The numeral 68 indicates a 75 thermometer associated with either buck 11 to thereby indicate the temperature of both bucks, since the heating means for both are alike.

I would state furthermore that while the 80 illustrated example constitutes a practical embodiment of my invention, I do not limit myself strictly to the exact details herein illustrated, since, manifestly, the same can be considerably varied without departure 85 from the spirit of the invention, as defined in the appended claims.

What I claim is:

1. In a pressing machine a turntable, a series of fixed pressing bucks disposed about 90 the table to turn therewith, a second series of presser bucks adapted to connect with the first mentioned presser bucks to effect the pressing operation, means carrying said second mentioned presser bucks and turning with the table, and a series of treadles also turnable with the table and adapted to effect the raising and lowering of said carrying means; together with separate burners for heating the presser bucks of the 100 respective pairs, means to supply water to the several presser bucks, a header, means to connect said header with a water pipe, connections between said header and said water supply means, and connections between the several burners and the several water supply means for the presser bucks. 105

2. In a pressing machine, a table, a fixed presser buck on the table, a second presser buck adapted to move toward and from the 110 first mentioned buck, a bell crank carrying said second mentioned buck and pivotally mounted to raise or lower the buck, a treadle connected with said bell crank to actuate the same up or down, means to effect frictional engagement between the bell crank and the treadle for interlocking the same to hold the movable presser buck against movement and means to release the frictional engagement between the bell crank 115 and treadle.

3. In a pressing machine, a table, a fixed presser buck on the table, a second presser buck adapted to move toward and from the 120 first mentioned buck, a bell crank carrying said second mentioned buck and pivotally mounted to raise or lower the second mentioned buck, a treadle, means to raise or lower the second mentioned buck by the 125 operation of said treadle, a spring-pressed 130

yielding frame on the treadle, a friction roller carried by said frame and a second friction roller on the bell crank adapted to engage the first-mentioned roller to effect an 5 interlocking engagement between said frame and the bell crank.

4. In a pressing machine, a table, a fixed presser buck on the table, a second presser buck adapted to move toward and from the 0 first mentioned buck, a bell crank carrying said second mentioned buck and pivotally mounted to raise or lower the second mentioned buck, a treadle, means to raise or lower the second mentioned buck by the 5 operation of said treadle, a spring-pressed yielding frame on the treadle, a friction roller carried by said frame and a second friction roller on the bell crank adapted to engage the first-mentioned roller to effect 20 an interlocking engagement between said

frame and the bell crank; together with a foot rest on the treadle having a dependent member adapted to engage the floor where the machine is emplaced for rocking the treadle and thereby disengaging the said 25 roller to release the bell crank from the treadle.

5. In a pressing machine, a table, a fixed presser buck on the table, a second presser buck adapted to move toward and from the 30 first mentioned buck, a bell crank carrying said second mentioned buck and pivotally mounted to raise or lower the buck, a treadle connected with said bell crank to actuate the same up or down, and means to effect 35 frictional engagement between the bell crank and the treadle for interlocking the same to hold the movable presser buck against movement.

SAMUEL GOLDSTEIN.
